UNITED STATES PATENT OFFICE.

SUMNER E. BROWN, OF DEDHAM, MASSACHUSETTS.

FOCUSING DEVICE FOR AUTOMOBILE HEADLIGHTS.

Application filed May 1, 1925. Serial No. 27,225.

The object of this invention is to provide a mounting for a light source which will permit greatly varied adjustment.

I have found particular need for a construction of this sort in connection with the focusing of light bulbs in automobile headlights. In this work it is essential that the mounting be capable of positioning the light with great accuracy and that it be easy of manipulation. It is also desirable that it be simply constructed.

My mounting satisfies all of the above conditions. It consists of a socket, adapted to receive a light bulb, and provided with an adjusting member in threaded engagement therewith and which projects outwardly through an opening in the rear of the head lamp casing. The adjusting member is free to rotate in the casing and, when rotated, its threaded portion moves the socket longitudinally. The aperture in the casing through which the member projects is sufficiently large so that a universal tilting movement of the latter is permitted and this, in combination with the longitudinal movement, provides a full range of adjustment. Thus by the manipulation of one member any desired positioning of the bulb may be obtained. I have also provided the adjusting member with means which preferably has clamping or frictional engagement with the casing to hold it in adjusted position. A portion of the clamping means just mentioned may also, if desired, serve somewhat after the fashion of a spring washer to hold the socket in its position of axial adjustment.

Referring now to the drawings which show one illustrative embodiment of my invention:

Figure 1 is a side elevation of a portion of an automobile headlight with parts broken away to better show my focusing device;

Figure 2 is a view taken on line 2—2 of Figure 1; and

Figure 3 is a view taken on line 3—3 of Figure 1.

I have shown at 2 the ordinary headlight housing and at 3 a portion of the usual reflector. The reference character 4 indicates a source of light, in this case a two filament incandescent bulb. This bulb is received within socket 6 in the customary manner and it is by adjusting the socket that the bulb is focused. I have shown at 8 the usual connections carrying current to the bulb.

The socket 6 fits loosely within opening 10 formed in the reflector 3, the edges of the reflector around the opening being turned back as at 12 to provide a fulcrum for the 60 socket. Sliding as well as rocking movement of the socket is thus provided for. In order to prevent relative rotation of the socket and the reflector the opening 10 is provided with a keyway 14 into which fits a supporting member 16 secured to the socket 6 and serving as a key. The other end of the member 16 is turned down and, if desired, may be formed into U-shape as shown 70 at 18 although this is not essential. The legs of the U are provided with aligned threaded apertures to receive the threaded shank of an adjusting member 20. This member 20 projects outwardly through an aperture 22 in the casing 2 and is provided 75 with an enlarged knurled head 24 for manipulation. A dished washer 26 has engagement with the outside of the casing 2 and with the head 24 and prevents inward movement of the member 20. With this construction when the member 20 is rotated the socket 6 is given rectilinear movement.

It will be noted that the opening 22 is circular and is enlarged so as to permit member 20 to have universal tilting movement to rock the socket 6. This, in combination with the axial adjustment, makes it possible to shift the bulb in any direction, so that it may be properly positioned no matter what inaccuracies may creep into the manufacture of various parts of the assembly. I call particular attention to the fact that all adjustments are under the control of the single adjusting member 20.

In order to hold the parts in any desired position of adjustment I have provided a second dished washer 28 which encircles the member 20, and is yieldingly forced into engagement with the inside of the casing 2 by spring 30 which at its other end reacts against the end 18 of the member 16. This spring serves as a spring washer in that it tends to force the members 18 and 20 in opposite directions, thereby maintaining the axial adjustment of the bulb. It also serves 100 to clamp the casing wall between the washers 26 and 28 and thus holds the socket in any selected position of rocking adjustment. At the same time the washers 26 and 28 effectively seal the casing against the entrance of 105 dirt and moisture.

It will be noted that all the parts of my

device are simple and may be cheaply made.

I claim:

1. The combination of a casing having an aperture therein, a reflector in the casing, a light support mounted in the reflector for tilting or rectilinear movement comprising a socket and a member secured to the socket having a return bend at one end provided with aligned apertures, a member having threaded engagement with one of said apertures and having a manipulative part projecting outwardly through the aperture in
- 5
- 10

said casing to effect adjustment of the lamp and friction means mounted on said part and adapted to yieldingly hold the member 15 in adjusted position.

2. In the combination as defined in claim 1 said friction means comprising a disc mounted on said member and a spring urging said disc into frictional engagement 20 with the casing.

In testimony whereof I affix my signature.

SUMNER E. BROWN.
